PER CROSBY GREGORY,
ATTOR.

UNITED STATES PATENT OFFICE.

GEORGE DRAPER, OF HOPEDALE, MASSACHUSETTS.

SPINDLE-BOLSTER.

SPECIFICATION forming part of Letters Patent No. 251,842, dated January 3, 1882.

Application filed June 24, 1875.

To all whom it may concern:

Be it known that I, GEORGE DRAPER, of Hopedale, in the county of Worcester and State of Massachusetts, have invented Improvements 5 in Spindle-Bolsters, of which the following is a specification.

This invention relates to improvements in spindle-bolsters for use in machines for twisting yarn; and it consists in a spindle having an 10 attached surrounding sleeve combined with a bolster arranged between said spindle and sleeve, said bolster being provided with a spiral groove, inlet and outlet passages, and a cup-like collar forming at the top of the bolster 15 an oil-receiving chamber, substantially as hereinafter specifically set forth and claimed.

The drawing represents one of my improved spindle-bolsters, with the bolster, spindle, sleeve, &c., in section. 20 The spindle is of the class known as the "compound" spindle, it being composed of a spindle proper, *a*, and a sleeve, *b*, attached at the top of the spindle *a*, the sleeve being provided with pins *b'*, to engage and turn the bobbin, thus making the sleeve a positive bobbin-holding sleeve. 25

Between the spindle and sleeve is a space, into which fits the upper portion of the bolster *c*, the bolster thereby steadyng the spindle near its upper end and the bobbin surrounding the sleeve, bolster, and spindle. The long bolster reduces the tendency of the spindle to vibrate at its top. The bolster *c* is provided with an oil-receiving opening, *d*, leading to the spindle, and oil, usually applied while the spindles are in motion, passes through such opening, and is carried upward about the spindle by the spiral groove *e*, leading from the bottom to the top of the bolster, where it is retained while the spindle is kept in rotation. At the top of the bolster or tube is a cup-like collar, *f*, with its upper end bent in toward the spindle, forming at the top of the bolster an oil-receiving chamber, (lettered *g*), and in the top 45 of the tube is an outlet, *h*. The chamber *g* has not a bottom outlet. It is impossible for lint or dirt to get into the oil at the top of the tube through the space between the sleeve and bolster, as the lip on the cup-like collar *f* prevents its passage. During the rotation of the 50 spindle the oil is drawn by the spiral groove

either in the bolster or in the spindle upward about the spindle, and such oil passes through the outlet *h* and over the top of the bolster into the chamber *g*, and all heavy and impure 55 or gritty matter of greater specific gravity than oil, should anything of the kind get into the oil, will settle in such chamber below the opening at *h*, and only the lighter oil will flow back from such chamber and down into the oil-cup. The provision of this outlet *h* above the closed bottom of the oil-receiving chamber at the top of the tube is of much importance, as grit once in the oil and allowed to move with it up and down the spindle will roughen the 60 latter and cause it to wear rapidly and run hard.

It is evident that the collar of the sleeve might be made as a whirl and as denoted in dotted lines, Figure 1; but such method of 70 driving the compound spindle would not be as desirable as to drive the compound spindle from the whirl *i*. The foot of the spindle is surrounded by a tube and cup, as usual. The top of the spindle is shouldered at *i'*, forming 75 a seat for the upper end of the sleeve, and is screw-threaded to receive a nut, *j*, to confine the sleeve to the spindle.

I do not claim a spindle with a sleeve permanently attached thereto, as claimed by J. B. 80 Bancroft in his application filed July 20, 1878.

I claim—

1. The spindle and its attached surrounding sleeve, in combination with the spirally-grooved bolster intermediate of the said spindle and sleeve, the cup-like collar at the top of the bolster forming the oil-chamber *g*, having an outlet, *h*, at its top, substantially as shown and described. 85

2. The spirally-grooved bolster having an oil-inlet and a cup-like collar, *f*, at its top, provided with an oil-chamber, *g*, and outlet *h*, combined with an internal spindle and an external sleeve, all substantially as shown and described. 90

In testimony whereof I have signed my name to this specification in the presence of two subscribing witnesses.

GEORGE DRAPER.
